UNITED STATES PATENT OFFICE

156,504

DRAWING IMPLEMENT

Robert S. Grant, Providence, R. I.

Application February 2, 1949, Serial No. 635

Term of patent 14 years

(Cl. D52—1)

To all whom it may concern:

Be it known that I, Robert S. Grant, a citizen of the United States, residing at Providence, State of Rhode Island, have invented a new, original, and ornamental Design for a Drawing Implement, of which the following is a specification, reference being had to the accompanying drawing, forming a part thereof.

Fig. 1 is a front view of a drawing implement embodying my new design; and

Fig. 2 is an edge view of the same.

I claim:

The ornamental design for a drawing implement, substantially as shown.

ROBERT S. GRANT.
